UNITED STATES PATENT OFFICE.

GEORGE FRANKLIN PICKETT, OF BROOKLYN, NEW YORK.

SHAFT FOR PAPER-ROLLS.

1,223,104.

Specification of Letters Patent. Patented Apr. 17, 1917.

Application filed July 12, 1916. Serial No. 108,966.

To all whom it may concern:

Be it known that I, GEORGE F. PICKETT, a citizen of the United States, and a resident of the city of New York, borough of Brooklyn, in the county and State of New York, have invented a new and Improved Shaft for Paper-Rolls, of which the following is a full, clear, and exact description.

This invention relates to supports for paper rolls and has particular reference to means for making a quick, easy, and effective gripping connection between the roll of paper, or its equivalent, and the supporting shaft.

15 Among the objects, therefore, of this invention is to provide a pair of cones for co-operation with the shaft, said cones being movable freely inwardly from the ends of the shaft into engagement with the roll of paper, and each of the cones being provided with a dog or pawl coöperating with a toothed portion of the shaft to prevent accidental outward movement thereof.

Another object of the invention is to provide for at least one of said cones, an improved means for projecting it forcibly into the adjacent end of the roll to set up the desired amount of frictional grip.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

40 Figure 1 is a vertical longitudinal section indicating my improvement applied to a roll of paper, the intermediate portions thereof being broken away; and

Fig. 2 is a vertical transverse section on the line 2—2 of Fig. 1.

The roll of paper is indicated at 10 and as usual has an open center 10' through which the shaft 11 is adapted to be projected. The shaft is provided on one side 50 with a longitudinal groove or keyway 12, and along the opposite side or any other convenient portion, the shaft is provided with a series of teeth 13 at each end, the teeth being inclined toward the middle of the shaft from both ends.

At one end of the shaft is shown a head

14 having a cone 15 extending toward the other end of the shaft and adapted to project into the opening of the roll. This head is adapted to be shoved into or toward the roll as far as convenient by direct operation and will there be locked from outward movement by means of a dog 16 having teeth engaging one or more of the teeth 13 of the shaft, the dog being projected into such engagement automatically by means of a spring 17 carried by the head and provided at its outer end with a finger piece 18 for releasing it when desired.

For the other end of the shaft, is provided another head 19 having a cone 20 projectable into the other end of the roll. The outer end of the head 19 consists of an extension 21 in the nature of a sleeve fitted to the shaft and provided with an external screw thread 22, preferably of left hand character. Between the threaded portion and the cone 20 is a reduced zone 23. The cone members 15 and 20 are held from rotation around the shaft by means of keys 24 and 25 of any suitable character projecting into the keyway 12.

26 indicates an abutment member fitted slidably upon the shaft adjacent the outer end of the extension 21 of the head last described. The abutment carries a dog 16, spring operated in a manner described in connection with the head 14, adapting the abutment member to be forced directly toward the roll, but preventing movement thereof in the other direction. The abutment carries a flange or collar 27 at its inner end, and just within this collar the face of the abutment is provided with a ball race 28.

29 indicates a hand wheel secured to a hub 30, the main portion of which is threaded to coöperate directly with the threaded portion 22 of the extension. The outer end of the hub is provided with a circumferential groove 31 into which screws 32, or their equivalents, project from the collar 27 of the abutment, and at the end of the hub is provided a ball race 33. A series of anti-friction balls 34 are located in these registering ball races 28 and 33, whereby the hand wheel and hub may be rotated with the minimum amount of friction upon the abutment, but the hub and abutment are prevented from separation even when the parts are separated from the shaft, by means of the pins or screws 32. The length of the hub is sub-

stantially equal to that of the threaded extension 21 and the smooth zone 23, and when the parts are assembled, the hub is turned around the head so as to bring the inner end 5 thereof close to the cone or with the outer ends of the head and extension lying substantially in the same plane. One or more set screws 35 are projected through the inner end of the hub into easy cooperation 10 with the smooth zone portion 23 of the head. These set screws limit the outward movement of the hub with respect to the head extension.

A series of dowel pins 36 are secured in 15 the head extension 21 parallel to the axis of the shaft and projecting into corresponding sockets 37 formed in the abutment member 26 and serve to prevent relative rotation of the abutment member. These dowel pins do 20 not prevent, however, the movement of the head 19 forwardly away from the abutment member.

This portion of the invention just described will be forced directly into contact 25 with the end of the roll of paper similarly to the setting of the head 14, and then to tighten the heads in the ends of the roll, the operator will turn the hand wheel and hub toward the right, causing thereby the cones 30 to approach each other forcibly, the head 19 being moved directly by the threads of the extension, the abutment member being stationary with respect to the shaft, and the other cone being drawn into the roll by virtue of the reaction of the shaft and the abutment member. The cones obviously may be of any desired length or inclination, and the threaded portion 22 of the head extension will be long enough to effect the desired 35 40 45 50 55 60 65 70 75 80 85 90 95 100

slipped freely in the opposite direction from the roll, or both heads may be removed from the shaft if desired.

I claim:

1. The combination with a shaft for paper rolls or the like, a lead secured to one end of the shaft, a head having a conical inner end slidably fitted upon the other end of the shaft and adapted to be moved by hand directly into contact with the roll, the latter head being provided with an extension having a threaded exterior surface, a hand wheel having an internally threaded hub cooperating with said threaded surface, an abutment member slidably longitudinally of the shaft freely in one direction, means to control the sliding movement of the abutment member in the other direction from the shaft, means connecting the abutment member and wheel hub to prevent endwise separation, but permitting relative rotation of the hand wheel, and means to prevent rotation of the slidable head.

2. In a device of the character set forth, the combination with a shaft having a head secured at one end thereof, of a head slidable along the other end of the shaft, said head having at its outer end an extension having a threaded portion and a smooth reduced portion, a hub fitted upon said extension and having an internally threaded portion cooperating with the threaded portion of the extension and having means projecting inwardly from the other portion of the hub into contact with the reduced smooth portion of the extension, the hub serving to force the head in one direction until limited by said inwardly projecting means, an abutment slidably fitted upon the shaft, means to connect the hub with the abutment member for free rotation but preventing endwise displacement of the hub, and means extending between the head extension and the abutment member preventing relative rotation of these parts but permitting endwise movement of one with respect to the other.

GEORGE FRANKLIN PICKETT.
